US00D936720S

(12) **United States Design Patent** (10) **Patent No.:** **US D936,720 S**
(45) **Date of Patent:** **** Nov. 23, 2021**

(54) **DRIVING MODULE FOR ROBOTS**

(71) Applicant: **LG ELECTRONICS INC.**, Seoul (KR)

(72) Inventors: **Yousook Eun**, Seoul (KR); **Soonho Jung**, Seoul (KR); **Hana Choi**, Seoul (KR); **Eunsil Mok**, Seoul (KR); **Jinsu Kim**, Seoul (KR); **Taewoo Yoo**, Seoul (KR)

(73) Assignee: **LG ELECTRONICS INC.**, Seoul (KR)

(**) Term: **15 Years**

(21) Appl. No.: **35/509,828**

(22) Filed: **Feb. 20, 2019**

(80) **Hague Agreement Data**

Int. Filing Date: **Feb. 20, 2019**

Int. Reg. No.: **DM/209050**

Int. Reg. Date: **Feb. 20, 2019**

Int. Reg. Pub. Date: **Jul. 17, 2020**

(51) **LOC (13) Cl. 15-05**

(57) **CLAIM**

The ornamental design for a driving module for robots, as shown and described.

DESCRIPTION

1. Driving module for robots

1.1 : Perspective

1.2 : Front

1.3 : Back

1.4 : Left

1.5 : Right

1.6 : Top

1.7 : Bottom

1.8 : Right, showing the driving module for robots with environment

1.9 : Right, showing the driving module for robots with environment

1.10 : Perspective

1.11 : Front

1.12 : Back

1.13 : Left

1.14 : Right

1.15 : Top

1.16 : Bottom

1.17 : Perspective, showing the driving module for robots with environment

1.18 : Perspective, showing the driving module for robots with environment

The broken lines showing a home hub robot in reproductions 1.8 and 1.17 and a movable refrigerator in reproductions 1.9 and 1.18 are provided for the purpose of illustrating environment of the driving module for robots and form no part of the claimed design.

1 Claim, 18 Drawing Sheets
